ELECTROPLATING RACK

Hugh F. Jones and Hedley R. Colby, Greenville,
Mich., assignors to Federal Mogul Corporation,
Detroit, Mich., a corporation of Michigan

Application January 19, 1949, Serial No. 71,714

2 Claims. (Cl. 204—297)

1

This invention relates to the art of electroplating and, in particular, refers to an improved rack for use in the plating of hollow objects such as cylinders, bearing elements and the like.

In the electroplating of hollow members such as cylinder liners, bearings, and the like it is often desired to deposit the plating material on only one surface of the member. Inasmuch as the entire member is submerged in the electrolyte, it has been necessary heretofore to employ stop-off coatings or other means for preventing contact with the electrolyte when selective plating of this nature was attempted. Depending upon the means employed, these expedients have either required additional steps in the processing of the member or inflexible and sensitive plating apparatus both of which contribute to the expense of plating without producing reliably satisfactory results.

It is thus an object of the present invention to provide a relatively simple and inexpensive rack for selectively plating hollow members which is economical of manufacture and easy to use but, nevertheless, produces dependable results.

Another object is to provide a rack of the type described which is capable of adjustment to accommodate various size hollow members.

A particular object is to provide a rack which will plate the inner and not the outer surface of hollow members.

The means whereby these and other objects of the invention are accomplished will be described in conjunction with the accompanying drawings wherein:

Figure 1 is a view in central vertical section through the improved plating apparatus;

Fig. 2 is a view in partial side elevation taken from the right of Fig. 1;

Fig. 3 is a view taken substantially along the line 3—3 of Fig. 1;

Fig. 4 is a view taken substantially along the line 4—4 of Fig. 1; and

Fig. 5 is a view taken substantially along the line 5—5 of Fig. 1.

As best shown in Fig. 1, the improved plating fixture has a frame, designated generally by the reference numeral 1, which is preferably formed by laterally spaced, longitudinal hanger straps 3 and 5 which are fixedly joined at their upper ends by the transverse beam 7. A longitudinal hanger hook 9 is affixed by welding or other suitable means to the beam 7 and has its upper end 11 formed into a hook or other suitable shape whereby the frame 1 may be suspended on the current carrying cathode bus bar C. The mem-

2

bers comprising the frame 1 are composed of current conducting material, such as stainless steel, so that the hanger straps 3 and 5 function additionally as electrodes.

Preferably, an anode 13 is insulatingly carried by the beam 7 of frame 1 by means of through bolt or rod 14 extending through a central longitudinally extending aperture 15 of the anode 13. A tapered bushing 16 which also serves as a nut is threaded to the lower end of the rod 14 and positions the anode 13 relative to the rod 14. The rod 14 extends upwardly through a central aperture in an insulating bushing 17 held within an aperture 18 in the beam 7. The upper end of the rod 14 extends upwardly of the bushing 17 and receives a nut 19 which acts to clamp the rod 14 and electrode 13 to the bushing 17. An anode conductor strap 21 is clamped between the bushing 17 and the nut 19 in electrical contact with the rod 14.

The means required to adapt the strap 21 for connection to the anode bus A depends upon the location of said bus relative to the cathode bus C. When it is spaced below the bus C, as shown, this means may include a block 25 of electrical insulating material, such as Micarta, having a central slot 27 of greater depth than the thickness of the hanger hook or cathode bar 9 in the bottom of which said hook is seated. Screws 29 may be used to fasten the block 25 to the hook 9. A spring type clip 31 adapted for quick connection to the bus A is mounted on the face of the block 25 by means of screws 33 which serve as conductors and pass through the block 35 and engage the strap 21.

The frame 1 which has been described thus includes side members 3 and 5 which are also electrodes connected to bus C. It also carries an anode 13 which is adapted for connection to a separate bus A and thus comprises an electrode for coaction with the electrodes 3 and 5. In accordance with this invention, hollow objects to be plated, which may be a stack of bearing elements, are mounted on the frame 1 so that the electrode 13 is within the bore thereof and the electrodes 3 and 5 are located outside of the object.

The support means, designated generally by the reference numeral 35, for mounting the objects in this manner includes longitudinally spaced, lateral platelike members or heads 37 and 39 which are adapted to each engage opposite ends of the objects to be plated so that said objects are longitudinally disposed between the members. This assembly of members 37 and 39

and the object to be plated is removable from the frame 1 and is adapted for rapid and simple mounting thereon. For this purpose the outer ends of the lower member 37 have lateral grooves 41 on the underside thereof which rest upon the upper surfaces of inturned flanges or shoulders 45 formed on the lower ends of the straps 3 and 5. By this means, in conjunction with the force of gravity, the support means 35 and object are attached to the frame 1. They may be disconnected and removed therefrom by lifting them until the edges of the groove 41 clear the flanges 45, rotating the assembly relative to the frame 1, and then lowering the assembly of support means and object from the frame.

Suitable means are provided to properly guide the movements of the support means 35 in assembly and disassembly with the frame 1. The electrode 13 may be conveniently employed as a guide or locating bar for this purpose. In order to receive it, the heads 37 and 39 are provided with guide bushings 47 and 49, respectively. These bushings are mounted in larger bushings 51 and 53, respectively, which are formed of suitable insulating material, such as Micarta, and are secured in suitable apertures in the members 37 and 39. It will thus be recognized that the electrode 13 has no electrical connection with the support means 35 and yet serves to guide longitudinal and rotary motion thereof relative to the frame 1, the tapered end 16 acting to facilitate initial alignment upon assembly. It is desirable upon submersion of the fixture to have electrolyte contact the interior surface of the hollow object mounted between the members 37 and 39, as well as the exterior, hence the bushings 51 and 53 are provided with a plurality of longitudinal passages 55 to permit flow of electrolyte through the object and support means 35 and to permit circulation thereof during the plating operation. Also the apertures 55 of the bushing 53 permit the escape of any gases formed during plating.

The support means 35 may be especially adapted to hold generally cylindrically-shaped hollow articles which may be sleeves or bearing elements D illustrated in the drawings. For this purpose, longitudinal, diametrically opposed, inwardly opening angle bars 57 and 59 are affixed to the underside of the plate 39. In order to make this connection laterally adjustable to accommodate sleeves D of various diameters, the bars 57 and 59 have laterally extending base portions 61 which may be integral therewith or preferably they may be blocks secured thereto by welding or other suitable means thereby permitting the use of standard angle iron for the bars 57 and 59. The base portions 61 are provided with slots 63. Screws 65 extend upwardly through the slots 63 and engage suitable threaded apertures 67 in the member 39 whereby the bars 57 and 59 are adjustable to provide the desired lateral spacing therebetween for reception of different sized objects. Preferably the bars 57 and 59 are adjusted so that they are equidistant from the longitudinal axis of the apertured bushings 51 and 53 whereby the bars 57 and 59 will center the cylindrical objects and in the case of the split sleeves D will clamp them together to form, in effect, a hollow article.

A pair of additional angle bars 69 similar in construction to the bars 57 and 59 but much shorter in length are adapted for laterally adjustable attachment to the lower member 37 by

means of the slotted flange blocks 71 and screws 73 extending therethrough into the member 37. The lateral adjustment is regulated so that the bars 69 engage and support the lower end portions of the bars 57 and 59 whereby they are maintained in position to securely hold the stack of articles to be plated throughout its length. The magnitude of the vertical adjustment of the headers 37 and 39 whereby the means 35 will accommodate varying heights of stacked articles to be plated will to a large extent be controlled by the length of the bars 69. Preferably the bars 69 are relatively positioned to provide a frictional telescopic fit with the bars 57 and 59. If desired, detent means may also be provided to increase the friction of the telescopic connection.

The upper end surfaces of the bars 69 are beveled as at 74 to provide for an easy assembly of the support means 35 since any outward flaring of the lower end portions of the bars 57 and 59 will be corrected by engagement thereof with the beveled surfaces 74 which will cam these end portions into alignment. The supporting means 35 so assembled separate and apart from the frame 1 may be easily handled as a unit and inserted into the frame 1 by merely sliding the unit on the anode 13 which is received within the apertured bushings 51 and 53. The means 35 is slid over the anode 13 until the lower head clears the flanges 45 after which the means 35 is rotated and slid outwardly until the recesses 41 engage the flanges 45. The frame 1 and means 35 so assembled may then be placed in the plating bath. When so assembled the restricted area contact between the flanges 45 and the head 37 provides a voltage drop therebetween by which the straps 3 and 5 are maintained at a more negative potential than the articles to be plated whereby any ions will tend to deposit on the straps 3 and 5 rather than on the backs of the articles to be plated.

A plating rack so constructed may be used in many different electrolytic solutions as well as with workpieces or articles to be plated of many different metals, it merely being necessary to provide enough voltage drop between the articles and the straps so that the ions will tend to deposit on the straps rather than the articles. It has also been found that under certain circumstances the cathode connection may be made directly from the articles or any of the metal portions of the removable article supporting portion of the rack and undesirable plating will not occur on the outside of the articles and under certain circumstances the straps 3 and 5 may even be entirely electrically isolated from the electrical plating circuit. As an illustration of these just-named circumstances, if the straps 3 and 5 are of stainless steel, the back or outer surfaces of the articles being plated are of carbon steel and the electrolytic acid is an acid fluoroborate, for example, HBF_4 , then the cathode return conductor may be connected at any point to the movable rack portion or to the rear or outer surfaces of the articles and the stainless steel straps 3 and 5 may be electrically isolated from the direct plating circuit. This operation as far as we have been able to explain it stems from the inherent action of the stainless steel with the electrolyte which renders the straps 3 and 5 negative with respect to the electrolyte.

We have found that when a rack such as the one illustrated is used to plate an alloy of ap-

proximately 90% lead and 10% tin on bearings from an electrolyte comprising $Pb(BF_4)_2$ and $Sn(BF_4)_2$ in the ratio of about 9 to 1 in an acid fluoroborate solution onto bearings having a three and one-eighth inch outside diameter of carbon steel that straps of stainless steel having a section dimension of one-quarter inch by one inch when positioned relative to each other as shown, and whether electrically connected directly in the plating current circuit or not, will prevent any substantial amount of plating on the outside of the bearings. If the plating current flows across the restricted area contacts and through the straps 3 and 5 better results are obtained and the rack is usable in a wider variety of electrolytes and for plating parts formed of a wider variety of metals. The relative areas of the straps and of the bearing backs is apparently not critical providing that the areas of the straps 3 and 5 are sufficient. If desired, a casing 75 of stainless steel having its inner surface uninsulated and its outer surface covered with an insulating material 77 such as rubber or the like may be used. This casing 75 may be held in place by bolts 81. This increases the negatively charged area and further tends to draw the metal ions thereto away from the outside surface of the bearings.

If desired, a casing 75 having an outer surface covered with insulating material 77 such as rubber or the like, may be used to surround the frame.

The manner in which objects are assembled and disassembled on the fixture has been explained above. After assembly the entire structure is submerged in the electrolyte to just beneath the hanger beam 7. The electrolyte is therefore in contact with the inner and outer surfaces of the object and with the electrodes 3, 5, and 13.

Current from the anode bus A flows through the clip 31, bolts 33, anode strap 21, rod 14 and anode 13 to the electrolyte. Current flows through the electrolyte to the articles D, then to the rods 57, 59, 69 and therethrough to the head 37. Current flows from the head 37 to the flanges 45 of the straps 3 and 5 from whence it flows through the beam 7 and hook 9 to the cathode bus C.

What is claimed and is desired to be secured by United States Letters Patent is as follows:

1. In a rack for electroplating hollow articles, a frame comprising an upper end element having a pair of spaced downwardly depending legs which are provided with inwardly projecting flanges at their lower end portions, an upper and a lower end member positionable between said legs, a first pair of angle bars carried by one of said end members and extending toward the other of said end members, and a pair of abutments carried by said other end member and clampingly engaging the extending end portions of said bars, said end members having a first dimension in a plane extending transversely of said legs and of a magnitude less than the distance between said flanges whereby said end members may be inserted longitudinally of the legs between said flanges into the space between said legs, said lower end member having a second dimension in said plane of a magnitude greater than the distance between said flanges but less than the distance between said legs, said second dimension being aligned with said flanges whereby said lower end member seats on and is supported by said flanges.
2. The combination of claim 1 in which said frame comprises one electrode, a second electrode is carried by but electrically insulated from said frame and extends downwardly between said legs and in which said upper end member is apertured to receive said second electrode.
